UNITED STATES PATENT OFFICE

2,457,285

TRAY

Harvey A. Stepner, Richmond Hill, N. Y.

Application May 14, 1946, Serial No. 669,720

1 Claim. (Cl. 155—188)

1

This invention relates to a tray, and more particularly to a tray having a refuse receptacle associated therewith adapted to be utilized in association with a chiropodist's or podiatrist's chair.

A primary object of this invention is the provision of an improved tray adapted to be attached adjacent the foot rest of a chiropodist's chair to facilitate the disposal of waste material and refuse utilized during the treatment of the feet.

An additional object of the invention is the provision of such a device providing improved sanitation and ease and efficiency in the disposal of such waste matter.

A further object of the invention is the provision of such a device which may be readily associated with and attached to such a chair, and provided with means whereby the relative position thereof with respect to the chair may be varied at the will of the operator.

A still further object of the invention is the provision of such a device which is sturdy and durable in construction, reliable and efficient in operation, and relatively simple and inexpensive to manufacture and assemble.

Other objects will in part be obvious and in part be pointed out as the description of the invention proceeds, and shown in the accompanying drawings, wherein there is disclosed a preferred embodiment of this inventive concept.

In the drawings:

Figure 1 is a side elevational view of one form of device embodying features of the instant invention, shown in position on a chiropodist's chair, the latter being indicated in dotted lines.

Figure 2 is an enlarged side view of the device shown in Figure 1, particularly in elevation, and partially in section.

Figure 3 is an enlarged top plan view of the supporting bracket for the device.

Figure 4 is a top plan view of the device on a reduced scale, certain concealed portions of the apparatus being indicated in dotted lines.

Similar reference characters refer to similar parts throughout the several views of the drawings.

Having reference now to the drawings, there is diagrammatically indicated at 10 a chiropodist's chair provided with a movable foot rest 11. The foot rest 11 is mounted on a bifurcated member 12 provided with a transverse flat base portion 13. The tray of the instant invention, generally indicated at 14, includes a flat plate 15 of generally rectangular configuration to the under-

2

side of which is attached a bracket 16 including a U-shaped supporting member 17 adapted to surround the bar 13 of the chair. The bracket 16 includes, as best shown in Figure 4, an extending tongue 18 having a slotted aperture 19 therein. A screw 20 secured to the bottom of the tray 15 extends through the slot 19 and is provided with a wing nut, which, when tightened, securely fastens the tray 15 to the bracket. Obviously, upon loosening the wing nut 21, the tray may be moved longitudinally, or rotated, to vary the position thereof, within the limits defined by the slot 19. Bolts 23 provided with nuts 24 are provided to secure the clamping bracket 15 about the member 13.

Referring back now to the tray 15, the device is provided along one side thereof with a flange 25, the flange being substantially perpendicular to the member 13 when the device is aligned with the slot 19 along the outer end thereof with a second flange 26 and a third flange 29 opposite flange 25. No flange is provided on the inner edge of the device which is the side opposite the flange 26. An aperture is cut in a corner of the device adjacent the juncture of the flanges 26 and 29, and provided with a depending peripheral flange 27 having internal threads thereon. A cylindrical receptacle 28 externally threaded, at its upper peripheral rim, is adapted to engage the corresponding threads of the flange 27.

From the foregoing the operation of the device should now be readily understandable. In use, the tray 14 is attached to the member 13 of the foot rest in the manner previously described by means of the depending bracket 17, and bolts 23 and nut 24. Suitable adjustment is made as to the angle of position of the tray by loosening the wing nut 21 on the bolt 20, and after the tray is adjusted, any waste material or debris removed from the feet of the patient is adapted to fall onto the tray surface 15. Due to the open sides of the device, such refuse may be readily swept into the receptacle 28, and, when desired, the receptacle 28 may be removed for emptying and disposal of the refuse.

From the foregoing it will now be seen that there is herein provided a device which accomplishes all the objects of this invention, and others, including many advantages of great practical utility and commercial importance.

As many embodiments may be made of this inventive concept, and as many modifications may be made in the embodiment hereinbefore shown and described, it is to be understood that all

matter herein is to be interpreted merely as illustrative and not in a limiting sense.

I claim:

In a tray adapted for use with the foot rest of a chiropodist's chair and including means detachable mounting said tray on said foot rest in forwardly subjacent relation thereto, the improvement comprising a plane surface on said tray, said surface being formed with a waste disposal aperture therein, a depending annular flange integral with said tray and surrounding said aperture, a waste receptacle for said tray, said receptacle being formed with an open top, and said flange and said top including complementary means for readily detachably connecting said receptacle to said flange below said aperture. 15

HARVEY A. STEPNER.
